HAIR CURLER

Maria Rosa Mendez Gil, Mexico City, Mexico

Application August 26, 1946, Serial No. 692,995
In Mexico February 13, 1946

20 Claims. (Cl. 132—36)

1

This invention is directed to an improved hair curler, and particularly to a device of such character designed to produce a permanent Marcel wave.

One object of the invention is to obtain an improved and distinctive Marcel hair wave characterized by the fact that adjoining longitudinal portions of the strands of hair are set in more definite and more permanent angular relation to each other than could be produced by prior curling devices.

Another object of the invention is to provide an improved hair curler having hair-engaging surfaces so shaped and arranged in relation to one another as to produce a wave having the desired shape characteristics and which is long lasting.

Another object of the invention is to provide an improved hair curler comprising removably associated parts providing opposing hair-engaging, wave-forming surfaces adapted to be pressed towards each other and secured to set the hair wave under pressure.

A further object of the invention is to provide an improved hair curler having movably associated parts providing opposing hair-engaging wave-forming surfaces, and including heating means for heating the wave-forming surfaces.

A more specific further object of the invention is to improve hair curlers of the type comprising suitably supported spaced curling pins by providing auxiliary cooperative curling means having a multiplicity of hair-engaging hollow surfaces adapted to fit over and cooperate with the individual curling pins. Preferably, but not necessarily in all cases, the auxiliary curling means will be equipped with suitable heating means for heating the hollow surfaces.

The invention will be understood from the illustrative embodiment thereof shown in the accompanying drawing, and the description thereof to follow.

In such drawings:

Fig. 1 is a perspective view of a preferred form of auxiliary curling means with the parts thereof in hair curling position.

Fig. 2 is a plan view of the auxiliary curling means shown in Fig. 1 with the parts in open position;

Fig. 3 is a side view of a known form of main curler with which the auxiliary curling means can be employed;

Figs. 4, 5, 6 and 7 are plan views of parts employed in the construction of the auxiliary curling means shown in Figs. 1 and 2; and,

2

Fig. 8 is a perspective view of an improved form of main curling means.

The main curling element comprises spaced curling pins mounted so as to extend in several angularly related rows in such manner that strands of hair can be wound alternately around the pins of the several rows. One such construction is shown in my prior U. S. Patent 2,248,527, granted July 8, 1941. In the embodiment of Figs. 1 to 10 of such patent there are two rows of spaced pins arranged along a common axis to extend in opposite directions therefrom and at right angles thereto. The respective rows of pins are mounted on a body comprising a pair of opposing rectangular hollow plates. Located between the plates and projecting outwardly beyond one of the longitudinal edges thereof is a laterally adjustable hair-engagement bar. As shown in Fig. 1 of the patent, strands of hair are alternately wound around pins of the respective rows over the bar. Such bar is provided with wedge surfaces on its interior side engageable with coating surfaces of a further bar mounted interiorly of the members for longitudinal movement effected through such coating surfaces to adjust the hair-engagement bar laterally to tension the strands of hair. The longitudinally movable bar is provided with a threaded end projecting beyond the ends of the hollow plates and provided with a wing nut through which longitudinal adjustment is effected. The curling element shown in Fig. 3 herein may be constructed in accordance with such embodiment of my prior patent but since various details of construction are not material to the present invention they are not here shown. In Figs. 3, 10 and 11 indicate oppositely extending rows of curling pins arranged upon a common axis and respectively mounted upon a pair of opposing plates 12 and 13. A hair-engaging bar 14 projects outwardly beyond one of the longitudinal edges of such plates. If bar 14 is to be made adjustable laterally this may be accomplished through a member mounted between the plates for longitudinal adjustment through a wing nut 16 engageable with its threaded end 15 through mechanism such as described in my prior patent which is referred to for details of construction since adjustment of bar 14 and the matter of accomplishing the same are not essential to the present invention and need not be provided.

The auxiliary curling mechanism designed to cooperate with the main curler comprises means having cavities receiving the curling pins and hair-engaging surfaces coactive with the curling

pins and other hair-engaging surfaces of the main curler. This may take a variety of forms comprising two, three or four separable parts provided with a multiple of recessed portions or cavities adapted to receive the individual curling pins after the hair has been wound thereon. In the embodiment shown in Figs. 1 and 2 the auxiliary curling means includes a first pair of segment-like hollow members 17 and 22. Projecting inwardly from the opposing interior faces 172 and 222 of such members are cavities 19 and 20 of semi-circular cross-section conforming to the shape of the pins. When members 17 and 22 are in operative position as shown in Fig. 1 it will be understood that each pair of cooperating cavities 19 and 20 will embrace one of curling pins 11 of the main curler as shown in Fig. 3. The other interior faces 171 and 221 of members 17 and 22 will cooperate with the surface of plate 13 of the main curler.

A similar second pair of segment-like members 18 and 21 have formed in their opposing interior surfaces 182 and 212 cooperating recesses or cavities 23 and 24 to receive pins 10. The other interior surfaces 181 and 211 of such members cooperate with the outer face of plate 12. The various segment-like members 17, 18, 21 and 22 may be formed of aluminum or other sheet metal where, as preferred, the members are to be made hollow instead of solid. In such case a rectangular sheet 25, shown in Fig. 4, may be bent along its medial line to provide the two interior faces of the members at right angles, or substantially so, to each other. The recesses or cavities can be formed in sheet 25 by die casting. A second sheet metal blank 26, shown in Fig. 5, forms the outer surface of the segment-like members and is provided with segment-like ends 27 and 28 which may be bent at right angles and assembled with member 25 after forming as just explained to form a complete segment-like member of the character shown in Figs. 1 and 2. Two members 25 and 26 may be joined together along their meeting edges in any suitable member, such as by soldering.

The auxiliary curling means comprising members 17 and 18, 21 and 22 may be removably mounted in association with the main curler in various ways, it being understood that the coacting hair-engaging surfaces of the main and auxiliary curling means should be tightened towards each other to press the hair between them and held in this relation throughout the hair waving operation. I prefer to assemble the various segment-like members into a single unit which can be applied to and removed from the main curler as an entirety. To this end I provide hinged supporting means to which the parts of the auxiliary curling means are adjustably mounted to permit them to assume their proper fitted relation with the parts of the main curler. The mounting means shown includes strips 29, shown in Fig. 6, which are clinched in pairs to the outer surfaces of each of members 17, 18, 21 and 22, being so formed as to provide slots. A pair of arms 30 and 31, shown in Fig. 7, are hinged together at their adjoining ends as indicated at 32. Members 17 and 18 are slidably mounted on arm 30 by threading the arm through the slots formed by strips 29, and members 21 and 22 are slidably mounted in a similar manner on arm 31. Arms 30 and 31 are preferably formed of stiff sheet metal and each bent to semi-circular form. In this manner, when arms 30 and 31 are swung from their open position as shown in Fig. 2 to

their closed position shown in Fig. 1, members 17, 18, 21 and 22 will together approximate a cylindrical cross-section. It will be understood that the cooperating pairs of members 17 and 22, and 18 and 21 can be adjusted towards each other in close fitting relation with the curling pins of the main curler. Thereafter the free ends of arms 30 and 31 may be clamped together in any suitable manner as by means of wing bolts 35 threaded through apertures 33 and 34 provided at the ends of arms 30 and 31. By tightening the wing bolts it will be evident that the coacting hair-engaging surfaces of the main curler and the auxiliary curling means will be caused to tightly press the hair between them and thus insure greater permanency of the wave.

While the embodiment of the auxiliary curling means shown in Figs. 1 and 2 is constituted of four relatively movable parts with obvious advantages, it is to be understood that in some cases the respective pairs of segment-like members 17 and 22, 18 and 21 may either be formed as integral units or secured together in fixed relation. The main intent of the auxiliary curling means is to provide cooperating hair-engaging surfaces coactive with, the hair-engaging surfaces of the pins and other parts of the main curler.

While the auxiliary curling means may be used cold it is preferred to provide for heating the same to insure a better Marcel wave. To this end, conventional electric heating units, not shown, are installed in each of members 17, 18, 21 and 22. A pair of electric cords 36 and 37 are provided with branches leading inwardly through one end of members 17, 18, 21 and 22 to the heating elements in such manner as to permit such members to be freely opened and closed and adjusted relative to each other as above explained. I do not confine myself to the use of electric type heaters, it being obvious that the segment-like members may be internally heated by introducing steam thereto through the substitution of flexible tubes for the electrical conductors 36 and 37.

In Fig. 8 is shown an improved form of main curler of the same general type as that shown in Fig. 3, but having structural differences of functional importance in producing a wave in which adjoining portions of the strands of hair are set in more definite and more permanent angular relation to each other. Therein two rows of pins 40 and 41 extend in opposite directions from a common axis in an arrangement similar to pins 10 and 11 of the embodiment of Fig. 3. Projecting laterally at right angles to the plane of the axes of the pins is a relatively thin member of wedge-like cross-section having opposite side surfaces 42 and 43 which converge towards each other at a shallow acute angle and meet in a relatively sharp longitudinal edge 44 running parallel to the plane of the axes of the pins and spaced laterally outward of the bases of the pins. Edge 44 engages the hair wound alternately around pins 40 and 41 and serves to produce a sharp set therein. The sharpness of the set is enhanced by the fact that the hair-engaging opposite sides 42 and 43 converge at a shallow angle. In the form shown, the member of wedge-like cross-section may be made of sufficient width to form the supporting base for pins 40 and 41. In such event it can be made of a single solid piece of metal, wood or plastic material, or made in separable sections. It will be understood, however, that the main func-

tion of the wedge-like member is to provide the hair-engaging edge 44 and the adjoining hair-engaging surfaces 42 and 43 in a position laterally outward of the bases of pins 40 and 41, and the same may be made as a separate element from, but attached to, a pin-supporting base of any suitable form and shape.

At one end of the wedge-like member is secured a semi-circular plate 45 to which is hinged at 47 a similar semi-circular plate 46. The plates are provided with coacting recesses 48 and 49 in which the hair is inserted before winding on the pins and around edge 44.

The improved hair curler of Fig. 8 will in some instances be used without the auxiliary curling means of Figs. 1 and 2 to provide a satisfactory Marcel wave in conjunction with suitable wave solutions. However, it is normally preferred to employ the same in conjunction with the auxiliary curling means before described. It will be understood that the auxiliary curling means is adaptable to use with the curler of Fig. 8, and in fact other pin-type curlers, with the same advantages as when used with the main curler shown in Fig. 3.

As already indicated, the embodiment of the invention herein illustrated is merely exemplary, and the scope of the invention is to be determined in accordance with the appended claims.

I claim:

1. A hair curler comprising a plurality of spaced apart upstanding hair curling pins, a base upon which the curling pins are mounted, and hair pressing means removably mounted upon the pins having hair-engaging surfaces and being formed with pin-receiving cavities individual to each of said pins and shaped to conform to the shape of the pins.

2. A hair curler comprising a plurality of spaced apart upstanding hair curling pins, a base upon which the curling pins are mounted, hair pressing means removably mounted upon the pins having hair-engaging surfaces and being formed with pin-receiving cavities individual to each of said pins and shaped to conform to the shape of the pins, and heating means adapted to heat the hair pressing means.

3. A hair curler comprising means having hair-engaging surface portions, spaced apart hair curling pins upstanding from said surface portions and hair pressing means removably mounted on said first means having pin-receiving cavities individual to each of said pins and shaped to conform to the shape of the pins, and having hair-engaging surface portions coactive with the hair-engaging surface portions of the first means.

4. A hair curler comprising means having hair-engaging opposite side faces, rows of spaced apart curling pins outstanding from the opposite side faces, and hair pressing means removably mounted on said first means having individual cavities receiving the curling pins of both rows and having hair-engaging surfaces coactive with the side faces of the first means.

5. A hair curler comprising means having hair-engaging opposite side faces, rows of spaced apart curling pins outstanding from the opposite side faces, and a heater removably mounted on the first means having individual cavities receiving the curling pins of the respective rows and having surfaces coactive with the side faces of the first means, and heating means for said heater.

6. A hair curler comprising means having hair-engaging opposite side faces, rows of spaced apart curling pins outstanding from the opposite side

faces, and hair pressing means removably mounted on one side of the first means having individual cavities receiving the pins of one row and having surfaces coactive with one side face of the first means, and separate hair pressing means removably mounted on the opposite side of the first means having individual cavities receiving the pins of the second row and having surfaces coactive with the opposite side face of the first means.

7. A hair curler according to claim 6, wherein each of the hair pressing means is hollow, and including heating means mounted in each of the hollow pressing means.

8. A hair curler according to claim 6, wherein each of the hair pressing means comprises a plurality of cooperative separable sections, each section being formed with pin-receiving cavity portions and surfaces coactive with a face of the first means.

9. A hair curler according to claim 6, wherein each of the hair pressing means comprises a plurality of cooperative separable hollow sections, each hollow section being formed with pin-receiving cavity portions and surfaces coactive with a face of the first means, and heating means mounted interiorly of each hollow section.

10. A hair curler according to claim 6, further including clamping means for securing the hair pressing means in pressing engagement with the first means.

11. A hair curler according to claim 6, further including hinged mounting means supporting the respective pressing means for swinging movement relative to each other and relative to the first means.

12. A hair curler according to claim 6, wherein each of the hair pressing means comprises a plurality of cooperative separable sections, and further including mounting means for the hair pressing means supporting the coacting separable sections for movement to and from each other and for removal as a unit of the coactive separable sections of both hair pressing means from the first means.

13. A hair curler comprising means having hair-engaging opposite side faces, curling pins spaced from each other in rows projecting outwardly from the opposite side faces, a pair of opposing separable pressing members on one side of the first means, each of substantially segmental cross-section, having bottom surfaces coactive with one face of the first means, and being formed with a series of complementary cavity portions in their opposing faces receiving the individual pins of one row, a similar pair of opposing separable pressing members having bottom surfaces coactive with the opposite face of the first means and a series of complementary cavity portions in their opposing faces receiving the individual pins of the other row, a plurality of circular supporting arms, means mounting the various pressing members for individual sliding movement lengthwise on the arms, said arms each comprising hinged sections and each section mounting certain of the pressing members, and means for securing the free opposite ends of the respective supporting arms.

14. A hair curler comprising a member having opposite hair-engaging side faces, curling pins spaced from each other in rows projecting outwardly from the opposite side faces of the member, the hair-engaging opposite side faces projecting laterally outwardly beyond the curling pins in converging relation and meeting in a wave-setting 75 sharp edge, hair pressing means removably

7
mounted on one side of said member formed with individual cavities receiving the curling pins of one row and having hair-engaging surfaces coactive with one of the converging side faces of said member.

15. A hair pressing attachment for hair curlers of the type having a multiplicity of spaced curling pins projecting outwardly from a support, said attachment having a hair pressing surface and individual pin-fitting cavities formed in said surface for receiving the curling pins of a curler, said cavities being individual to each of said pins.

16. A hair pressing attachment for hair curlers of the type comprising a plurality of rows of spaced apart pins projecting outwardly from opposite sides of a support, said attachment comprising a plurality of opposing hair pressing members having individual cavities for receiving the pins of the respective rows of a curler and having hair pressing surfaces adjoining said cavities, and means for removably mounting the opposing hair pressing members on a curler.

17. A hair pressing attachment according to claim 16, further including electric heating means for each of the pressing means.

18. A hair pressing attachment according to claim 16, wherein each hair pressing member is formed as a plurality of separable coating sections, each section being formed with a part of each curling pin receiving cavity, and mounting means for removably mounting all the pressing sections in operative position on a curler, and for separation of the coating sections of each pressing member.

19. A hair curler comprising a first row of curling pins arranged in spaced relation along an axis and projecting outwardly from the axis in one direction, a second row of curling pins arranged in spaced relation along the axis in stag-

gered relation to the pins of the first row and projecting outwardly from the axis in the opposite direction, and means interposed between the rows of pins including a base portion upon which the pins are mounted and a projecting portion extending outward laterally at right angles to the plane of the pins, said projecting portion having hair-engaging outwardly converging opposite side surfaces meeting in a sharp hair-setting longitudinal edge located in outwardly spaced relation to the bases of the pins of the two rows.

10 20. A hair curler comprising a first row of curling pins arranged in spaced relation along an axis and projecting outwardly from the axis in one direction, a second row of curling pins arranged in spaced relation along the axis in staggered relation to the pins of the first row and projecting outwardly from the axis in the opposite direction, and a relatively thin member mounting the pins of the two rows, said member being of wedge-shaped cross-section, the opposite sides of the member converging laterally in a direction at right angles to the pins and meeting in a sharp hair-setting edge.
